UNITED STATES PATENT OFFICE.

WILLIAM S. WHEATFIELD, OF BALTIMORE, MARYLAND.

DESIGN FOR A BUCKLE.

SPECIFICATION forming part of Design No. 25,794, dated July 21, 1896.

Application filed March 24, 1896. Serial No. 584,719. Term of patent 7 years.

To all whom it may concern:

Be it known that I, WILLIAM S. WHEATFIELD, a citizen of the United States, residing in the city of Baltimore, State of Maryland, have invented and produced a new and original Shape or Configuration for an Article of Manufacture—to wit, Buckles—of which the following is a specification, reference being had to the accompanying drawing, showing the same.

The leading feature of my design consists of the shape of the buckle and the configuration of the front edge thereof.

In the drawing, 1 represents the frame. 15 2 is the front portion of the frame, made much wider than the rest of the frame and

having an undulating outline, rounded in the center and receding on the sides of the center.

3 is the bar located in the center of the frame and provided with tongues 4. 20

The purpose of making the buckle-frame wide in front is to permit of stamping thereon a trade-mark.

What I claim, and desire to secure by Letters Patent, is—

The design for a buckle substantially as herein shown and described.

WILLIAM S. WHEATFIELD.
